GAME DEVICE

Millard H. Ronzone, New York, N. Y., assignor to
Ronzone & Lange, New York, N. Y., a firm com-
posed of Millard H. Ronzone and Herman Lange

Application June 9, 1938, Serial No. 212,709

6 Claims. (Cl. 273—99)

This invention has to do with amusement or game devices and is in the nature of an improvement upon a game device of the type disclosed in prior United States Letters Patent, No. 5 2,095,390, granted October 12, 1937.

In a game of the character set forth, the player standing in a playing position at a distance from a vertically disposed base having outwardly projecting pegs attempts to swing a suspended ring 10 onto the pegs. If successful, the player is required to walk from his position to remove the ring from the pegs and return to the playing position.

The present invention is directed to means 15 controlled by the player from the playing position for displacing the ring from any one of the pegs without the necessity of leaving the playing position.

More particularly the invention resides in providing 20 remotely controlled manually actuated means for retracting the pegs from a normal position projecting through the base to thereby displace the rings therefrom.

With the above and other objects in view, the 25 invention is set forth in greater detail in the following specification, illustrated in the accompanying drawing and pointed out in the appended claims which cover variations and modifications thereof.

30 In the drawing:

Fig. 1 is a perspective view of a game device constructed in accordance with the invention and illustrating the pegs in normal position projecting through the base.

35 Fig. 2 is an enlarged fragmentary rear face view thereof.

Fig. 3 is a longitudinal sectional view taken approximately on the line 3—3 of Fig. 2 and illustrating the pegs in partly retracted position.

40 Fig. 4 is an enlarged cross sectional view taken on the line 4—4 of Fig. 2 and illustrating the pegs in partly retracted position.

Fig. 5 is a view similar to Fig. 4 and illustrating 45 a modified form of the invention.

45 Referring to the drawing by characters of reference, 10 designates a base having a plane surface 11 and a plurality of projections or pegs 12 projecting outwardly from the plane surface and preferably arranged in arcuate spaced relation.

The base 10 is adapted to be supported in a vertical upright position with its plane surface 11 disposed vertically, and any suitable means for securing the same in said position may be 50 employed, such as the clamping device 13 where-

by the same may be secured to the side stile of a doorway as illustrated.

Secured to the base 10 and projecting outwardly and upwardly therefrom is an arm 14 from the free end of which is suspended, by 5 means of a flexible cord 15, a ring 16 which is adapted upon swinging movement to be engaged over any one of the projections or pegs 12 by a player standing in a playing position at a distance from the base 10. The free end of the arm 14 10 is located at a point which is substantially the radius of the arc upon which the pegs or projections 12 are arranged.

The present invention is directed to means for displacing the ring 16 from any one of the pegs 15 12 which means is controlled and actuated by the player without the necessity of his leaving the playing position.

In the form of the invention illustrated in Figs. 1 to 4 of the drawing, the pegs 12 are secured at 20 their inner ends to a strip 17 located in the rear of the base 10 with the pegs slidably projecting through openings 18 therein. Secured to the rear face of the base 10 is an angle bracket 19 having a downturned end 20 provided with an 25 opening 21 therein in which is received a rod 22 projecting rearwardly from the strip 17, said rod in the present instance being threadedly anchored in the central peg 12. The rod 22 is slid- 30 able in the opening 21 to cooperate with the pegs 12 35 slidable in the openings 18 for guidedly mounting the strip 17 for movement from a normal position adjacent the base 10 with the pegs in active position projecting through the openings 18, to a retracted position spaced from the base 35 10 and with the pegs retracted to a position disposing their outer ends substantially flush with the outer face of the base 10 and vice-versa.

In order to provide remotely controlled means 40 adapted to be actuated by the player for moving the pegs 12 to the retracted position, a pull cord 23 is trained through a guide opening 24 in the downturned end 20 of the angle bracket 19 with the inner end of the cord connected to the strip 17 and the free terminal end thereof preferably provided with a manipulating knob 25 adapted to be grasped by the player for exerting a pull on the cord and a consequent rearward movement of the strip 17 and a retraction of the pegs 12 to dislodge the ring 16 engaged over any one of said 50 pegs. In order to effect the movement of the pegs 12 to their active position projecting through the openings 18 and to tension the same against retraction thereof, a coiled expansion spring 26 surrounds the rod 22 and is interposed between the 55

strip 17 and the downturned end 20 of the bracket 19.

In the form of the invention illustrated in Fig. 5 of the drawing, the rod 30 is secured to the 5 downturned end 20 of the angle bracket 19 and extends forwardly thereof into a bore 31 in the central peg 12 and which bore 31 is of sufficient depth to permit of the sliding of the central peg 12 on the rod 30 to dispose the strip 17 and pegs 10 12 in retracted position with the ends of the pegs substantially flush with the outer face of the base 10. In this form of the invention, the coiled expansion spring 26 likewise functions to move the strip 17 and pegs 12 from retracted position to a 15 normal position with the pegs protruding through the openings 18 for receiving the ring 16 there-over.

What is claimed is:

1. In a game device, a base having a substantially vertically disposed plane forward surface and being formed with a plurality of spaced openings extending transversely therethrough, a strip located at the rear of the base, a plurality of pegs carried by said strip and protruding forwardly thereof in sliding engagement with said openings, means for normally moving the strip to a position to dispose the pegs in protruding relation with said openings and outwardly from said plane surface, a ring suspended for swinging movement 30 for engagement over said pegs, and manually controlled means for retracting the strip and the pegs to a position to dispose the outer end of the pegs adjacent the plane surface of the base for displacing the ring from the pegs when engaged 35 thereon.

2. In a game device, a base having a substantially vertically disposed plane forward surface and being formed with a plurality of spaced openings extending transversely therethrough, a strip located at the rear of the base, a plurality of pegs carried by said strip and protruding forwardly thereof in sliding engagement with said openings, means disposed at the rear of the base engaging said strip for exerting a tension thereon to normally move the same to a position to dispose the pegs in protruding relation with said openings and outwardly from the plane surface of the base, a ring suspended for swinging movement for engagement over said pegs, and manually controlled 40 means for retracting the strip and the pegs against the action of said first mentioned means to a position to dispose the outer ends of the pegs adjacent the plane surface of the base for dislodging the ring from the pegs when engaged 45 thereon.

3. In a game device, a base having a substantially vertically disposed plane forward surface and being formed with a plurality of spaced openings extending transversely therethrough, a strip located at the rear of the base, a plurality of pegs carried by said strip and protruding forwardly thereof in sliding engagement with said openings, means carried by the base and disposed at the rear thereof for exerting a tension on the strip to normally move the same to a position to dispose the pegs in protruding relation with said openings and outwardly from the plane surface of the base, a ring suspended for swinging movement for en-

gagement over said pegs, manually controlled means for retracting the strip and the pegs against the action of said first mentioned means to a position to dispose the outer ends of the pegs adjacent the plane surface of the base for dislodging the ring from the pegs when engaged 5 thereon, and means at the rear of the base for guiding the strip in its movements.

4. In a game device, a base having a substantially vertically disposed plane forward surface 10 and being formed with an opening extending transversely therethrough, a peg mounted for sliding movement in said opening, means for normally moving the peg to an active position protruding through said opening and projecting 15 outwardly from said plane surface, a ring suspended for swinging movement for engagement over said peg, and manually controlled means for retracting the peg to a position disposing the outer end thereof adjacent the plane surface of 20 the base for displacing the ring from the peg when engaged thereon.

5. In a game device, a base having a substantially vertically disposed plane forward surface and being formed with a plurality of arcuately 25 spaced openings extending transversely therethrough, a strip located at the rear of the base, a plurality of pegs carried by said strip and protruding forwardly thereof in sliding engagement with said openings, a ring suspended for swinging 30 movement for engagement over said pegs, a bracket carried by the base at the rear thereof, an expansion spring interposed between said bracket and said strip for normally moving the same to a position to dispose the pegs in protrud- 35 ing relation with said openings and outwardly from said plane surface, manually controlled means for retracting the strip and the pegs against the action of said spring to a position to dispose the outer ends of the pegs adjacent the 40 plane surface for displacing the ring from the pegs when engaged thereover, and interengaging means carried by the bracket and strip for guiding the strip in its movements.

6. In a game device, a base having a substantially vertically disposed plane forward surface and being formed with a plurality of arcuately spaced openings extending transversely therethrough, a strip located at the rear of the base, a plurality of pegs carried by said strip and protruding forwardly thereof in sliding engagement with said openings, a ring suspended for swinging movement for engagement over said pegs, a bracket carried by the base at the rear thereof, an expansion spring interposed between said bracket 55 and said strip for normally moving the same to a position to dispose the pegs in protruding relation with said openings and outwardly from said plane surface, manually controlled means for retracting the strip and the pegs against the 60 action of said spring to a position to dispose the outer ends of the pegs adjacent the plane surface for displacing the ring from the pegs when engaged thereover, and means carried by the bracket and engaging an opening in one of said 65 pegs for guiding the strip in its movements.
